UNITED STATES PATENT OFFICE.

ROBERT S. MOUNCE, OF RUTHERFORD, NEW JERSEY, ASSIGNOR TO THE CURTAIN SUPPLY COMPANY, OF CHICAGO, ILLINOIS, A CORPORATION OF ILLINOIS.

RELEASABLE HANDLE FOR DIAPHRAGM-CURTAINS.

1,314,533.

Specification of Letters Patent.

Patented Sept. 2, 1919.

Application filed April 14, 1919. Serial No. 290,029.

To all whom it may concern:

Be it known that I, ROBERT S. MOUNCE, a citizen of the United States, residing at Rutherford, in the county of Bergen and 5 State of New Jersey, have invented certain new and useful Improvements in Releasable Handles for Diaphragm-Curtains, of which the following is a specification.

My invention relates to side curtains for 10 use on the interiors of coach vestibules and has for its object the provision of a releasable handle therefor to provide an automatic uncoupling in case of emergency.

A vestibule curtain of this type is usually 15 secured to the vestibule of one coach just inside of the diaphragm at one side of the passageway by means of a spring-mounted curtain roller the tension of which tends to wind up the curtain while its free edge is 20 arranged to be detachably coupled to the vestibule of the adjacent connected coach by a handle on the curtain that is engaged with a hook on the vestibule to which the curtain is detachably secured. A companion curtain 25 is similarly mounted on the opposite side of the passageway, the spring roller mounting of one curtain being opposite the detachable handle of the other curtain, one curtain being carried by one coach and the 30 other by the adjacent coach.

In practice these curtains are often torn by separation of the coaches while the curtain is connected to the two vestibules. The trainmen in charge of the handling of 35 coaches in switch yards and elsewhere frequently forget to uncouple the curtains when they uncouple the coaches and thus as the coaches separate the curtains are torn.

The present invention provides a quick 40 automatic release of the curtain handle from the adjacent coach in such circumstances, the arrangement being such that the connection between the handle and the coach will sustain all normal strains due to the 45 spring pull of the roller but will yield or give way when subjected to abnormal strains.

In order that the invention and the manner of its use may be readily understood a 50 preferred embodiment of the same is set forth in the accompanying drawing and in the following detailed description, it being understood that as the invention is susceptible of embodiment in constructional 55 forms other than that specifically illus-

trated and described, the drawing and description are to be taken in an illustrative and not in an unnecessarily limiting sense. In the drawings

Figure 1 is a side elevation of a handle, 60 showing the same associated in connected relation with the car post and curtain;

Fig. 2 is a top plan or end view of the handle;

Fig. 3 is a side elevation with the side 65 plate removed to show the interior mechanism; and

Fig. 4 is a fragmentary view showing a slight modification.

Having particular reference to the drawings, the vestibule curtain is indicated at 11 with its reinforced free edge at 12. A post 13 of an adjacent car is provided with a hook 14. It is to be understood that that edge of the curtain 11 opposite the reinforced edge 75 12 is mounted upon a spring-actuated roller in the usual manner, said roller being suitably mounted upon the car adjacent that carrying the post 13.

The quick-releasable handle of the present 80 invention comprises generally a foundation or reinforcing bar 15 advantageously square in cross section with its ends 15^a and 15^b outturned to constitute a yoke-like member. Upon the two side faces of the yoke member 85 15 at the ends thereof are riveted or otherwise suitably secured side plates 16 and 17 which advantageously extend around the end of the yoke member and upon the opposite side in opposition to the first portion of 90 said plate thus providing housings with opposed openings, that is to say the opening of one housing facing that of the other. These side plates 16 and 17 have projecting wing 95 portions 16^a and 17^a which overlie and partly embrace the reinforcing rods 12 of the curtain and other wing portions 16^b and 17^b hinged to the plates proper and embracing the opposite side of the curtain rod reinforcement, the same being firmly attached 100 to the curtain by means of the rivets or bolts 18.

Within the housing 17 is pivoted at 19 a bolt or shackle 20 arranged to span the space between the two housings carried by the ends 105 15^a and 15^b of the yoke member. Within the housing 16 is pivoted at 21 a detent 22 normally disposed at right angles to the shackle or bolt 20 and provided with a V-shaped recess 23 in its side for the recep- 110

tion of the correspondingly shaped end 20^a of the bolt or shackle. This detent 22 is normally pressed into engagement with the end of the bolt or shackle by means of the 5 compression spring 24 disposed within the housing 16 at the rear of the detent.

In Fig. 4 of the drawing is shown a slight modification wherein a compression leaf spring is substituted for the compression 10 coil spring of Fig. 3. Here the spring 24^a is riveted to the outturned end 15^a of the reinforcing bar 15 instead of being mounted upon the end wall of the housing as in the case of the coil spring. The action is precisely the same in both instances.

It will be observed that by reason of the frictional engagement of the end of the bolt or shackle within the V-shaped recess of the detent, which engagement is yieldingly maintained by means of the spring 24, my improved handle will remain closed and in engagement with the hook 14 under such strain as is applied thereto by the spring-mounted curtain rod, and may be used as an ordinary handle for pulling out the curtain for operative connection with the coach, and furthermore the said handle will not open up as long as the two coaches remain coupled together. However, it will 20 release the end of the shackle or bolt, permitting the same to open up and to disengage from the hook 14 in case of abnormal strain considerably less than that required to tear or rip the curtain, wherefore it follows that if the curtain is allowed 30 to remain coupled to the two vestibules while the coaches are pulled apart, this improved handle will automatically release the edge of the curtain thus avoiding the 35 tearing or destruction thereof.

I claim:

1. In a vestibule curtain, the combination with a spring-actuated roller mounting attached to one edge thereof, of a handle attached to the free edge of said curtain, said handle including a yoke member, a bolt pivoted to one side of and spanning the spread of the yoke, a spring-pressed detent mounted in the side of the yoke and 45 yieldingly engaging the free end of the bolt, whereby the bolt will sustain the normal spring pull of the roller but will yield to abnormal strain.

2. The combination with a spring-actuated curtain mounted at one edge upon a roller, of a quick-release handle attached to the free edge of said curtain, said handle including a yoke member, a bolt pivoted to one side of and spanning the spread of the 50 yoke, a spring-pressed detent mounted in the other side of the yoke and acting in a direction longitudinally of the bolt to frictionally engage the free end thereof, whereby the bolt will sustain the normal spring

pull of the roller but will yield to abnormal strain.

3. The combination with a curtain mounted at one edge upon a spring-actuated roller, of a quick release handle attached to the free edge of said curtain, said handle including a yoke-shaped bar, side plates attached to the out-turned ends of the bar to provide housings with openings opposed one to the other, a bolt pivoted to the housing at one side of the yoke and spanning the spread thereof, a spring-pressed detent mounted in the housing at the other side of the yoke and yieldingly engaging the free end of the bolt whereby the bolt will sustain the normal spring pull of the roller but will yield to abnormal strain.

4. The combination with a curtain mounted at one edge upon a spring-actuated roller, of a quick release handle attached to the free edge of said curtain, said handle including a yoke-shaped bar of square cross section, side and end plates attached to the out-turned ends of the bar to provide housings with openings opposed one to the other, a bolt pivoted within the housing at one side of the yoke and spanning the spread thereof, and a spring-pressed detent pivoted within the housing opposite the bolt pivot and extending at right angles to the bolt and frictionally engaging the free end of the bolt, whereby the bolt will sustain the normal spring pull of the roller but will yield to abnormal strain.

5. The combination with a curtain mounted at one edge upon a spring-actuated roller, of a quick release handle attached to the free edge of said curtain, said handle including a yoke member, a bolt pivoted to one side of and spanning the spread of the yoke, a detent pivoted at the other side of the yoke and extending at right angles to the bolt, a V-shaped notch in the free end of the detent to receive the correspondingly shaped free end of the bolt, and a spring at the rear of the detent and acting at right angles thereto to press the detent into engagement with the bolt end whereby the bolt will sustain the normal spring pull of the roller but will yield to abnormal strain.

6. The combination with a curtain mounted at one edge upon a spring-actuated roller, of a quick release handle attached to the free edge of said curtain, said handle including a yoke-shaped bar, side plates attached to the out-turned ends of the bar to provide housings with openings opposed one to the other, a bolt pivoted to the housing at one side of the yoke and spanning the spread thereof, a detent pivoted within the housing opposite the bolt pivot and extending at right angles to the bolt, a V-shaped notch in the free end of the detent to receive the correspondingly shaped free end

of the bolt, and a compression spring within the housing at the rear of the detent and acting at right angles thereto to press the detent into engagement with the bolt, where-
5 by the bolt will sustain the normal spring pull of the roller but will yield to abnormal strain.

In testimony whereof I have hereunto signed my name in the presence of two sub-
scribing witnesses.

ROBERT S. MOUNCE.
